UNITED STATES PATENT OFFICE

EDWIN B. ARTHUR AND FRANK G. LESLIE, OF IRWIN, PENNSYLVANIA

ASH TRAY

Application filed March 31, 1932. Serial No. 602,262.

This invention relates to improvements in ash trays and more particularly to cigarette-holding means applicable to any ash tray of the receptacle or container type.

5 It is among the objects of the invention to provide an ash tray embodying means for securely holding a cigarette in a horizontal position and which shall be adapted to retain the cigarette in this position regardless 10 of its length or whether it is abandoned by the smoker.

Another object of the invention is the provision of cigarette gripping means for ash trays which shall function to extinguish 15 a burning cigarette which has been placed therein and retained for a given length of time, thereby preventing the cigarette from dropping outside of the container as is customary in conventional form of ash trays 20 now in use.

Another object of the invention is the provision of cigarette-holding means for ash trays which lends itself to become an integral embodiment of the ash tray itself irrespective 25 of whether the receptacle is constructed of stamped metal or formed of glass or other refractory substances.

These and other objects of the invention will become more apparent from a consideration of the accompanying drawing constituting a part thereof in which like reference characters designate like parts and in which Figure 1 is a perspective view of an ash tray embodying the principles of this invention; Figure 2 a side elevational view thereof, partially in section, illustrating the manner of holding the cigarette on the tray or receptacle; Figure 3 a cross sectional view of the holding or gripping means as will be hereinafter explained, and Figure 4 a modified form of receptacle employing the cigarette holding means utilized in the structure of Figure 1 of the drawing.

With reference to the several figures of the drawing, the structure therein illustrated comprises an ash tray 1 of relatively shallow construction having a base 2 on which it is supported, the tray 1 having its outer periphery interrupted at 3 to constitute hook-like members having undercut portions

4 of a dimension somewhat smaller than the size of the conventional cigarette.

The hook portion 4 is proportioned to engage a substantial part of the periphery of a cigarette as is clearly shown in Figure 3 of the drawing, and the distance between the hook end 5 and the upper edge of the tray is such as to effect a decided crimping of the body of the cigarette when it is placed therein.

When placing a cigarette in the hook portions in the manner shown in Figure 2 of the drawing, it will be firmly held in a substantially horizontal position as shown in this view, and if a burning cigarette is left to burn when so held in the ash tray, it will burn no further than the point at which it is gripped by the hook-like member 5 at which place its oxygen supply is cut off and it will go out without however dropping from the tray since the gripping effect of the hook 5 is sufficient to hold it in place.

In the construction shown in modified form in Figure 4 of the drawing, the hook-like elements 5 are produced by cutting out the side wall of the tray forming recesses 6 therein which correspond to the curved portion 4 of the projecting hook members in Figure 1 of the drawing.

The function of this form is precisely the same as that hereinafter described, and it will hold a cigarette horizontally and prevent it falling from the tray when it is burned down to the point where it is gripped the same as in the case where the hook-like gripping element projects upwardly from the edge of the tray as in Figures 1 and 2.

The ash trays or receptacles may be produced from sheet metal stampings or they may be molded glass articles without involving any difficulties in the manufacture of the hook elements, and when constructed in either of the forms shown in Figure 1 or 4 of the drawing, the gripping or holding elements are conveniently accessible to the user for holding cigarettes which are placed therein by merely sliding them into the projecting hook.

It is evident from the foregoing description of the invention that cigarette ash trays,

receptacles, or the like, embodying the hook-like holding means adapted for crimping the cigarettes will hold the cigarette in such a way that it is kept in a sanitary condition, as the end which has been in the smoker's mouth will not contact any part of the tray. The holder will also prevent the dropping of the cigarettes which causes burning of table covers or the varnish of the support on which the ash tray is placed and such devices will further function to extinguish the cigarette if it is left in the holding element of the ash tray.

Although one embodiment of the invention has been herein illustrated and described, it will be obvious to those skilled in the art that various modifications may be made in the details of construction and in the adaptation of the principles herein disclosed without departing from the principles thereof.

We claim herein as our invention:

1. In an ash tray the combination of a receptacle portion for receiving the ashes of cigarettes or the like of hooklike projec-

tions extending upwardly therefrom, the hook portions of which are adapted to intimately engage a cigarette and securely hold it in position.

2. In an ash tray the combination with a receptacle portion for receiving tobacco ashes or the like of cigarette gripping elements formed integrally with the side wall of the receptacle portion and constituting hook-like members adapted to crimp the cigarettes placed therein to securely hold them in position and prevent burning of the cigarettes beyond the point of engagement of the holding means.

3. Ash receptacles for cigarettes or the like comprising a container having notches formed in the side wall thereof for receiving and holding cigarettes, said notches being of hook-like form, the dimensions of which are less than the diameter of the cigarette to effect gripping engagement of the cigarette when placed therein.

EDWIN B. ARTHUR.
